AUTOMOBILE FLOOR MAT

Jack W. Dudley, 48 Woodland Drive,
Poland, Ohio 44514

Filed June 6, 1966, Ser. No. 2,574

Term of patent 3½ years

(Cl. D9—6)

I claim:

The ornamental design for an automobile floor mat, as shown and described.
